UNITED STATES PATENT OFFICE.

GEORGE E. FERGUSON, OF NEW YORK, N. Y., ASSIGNOR TO WILLIAM E. SILVERTHORNE,
OF NEW YORK, N. Y.

PROCESS OF TREATING FIBROUS MATERIALS.

1,268,446.

Specification of Letters Patent. Patented June 4, 1918.

Application filed April 9, 1913, Serial No. 759,930. Renewed October 27, 1917. Serial No. 198,873.

To all whom it may concern:

Be it known that I, GEORGE E. FERGUSON, residing at New York, in the county of New York and State of New York, have invented 5 certain new and useful Improvements in Processes of Treating Fibrous Materials, of which the following is a specification.

This invention relates to a process or method for rendering fibrous or porous materials impervious to moisture.

The principal object of the invention is to provide a new and improved process by the use of which fibrous or porous materials may be made more thoroughly proof against absorption and penetration than heretofore.

A further object is to provide an improved process by the use of which fibrous or porous materials may be impregnated with a suitable non-porous and moisture repellent element.

A further object is to provide a process as above, wherein a higher degree of impregnation by the moisture repellent element, than heretofore, may be attained, so that the moisture repellent element will appear mostly 25 within the body of the treated material rather than upon the surface thereof.

A further object is to provide a process by the use of which the fiber, of such materials as cardboard, paper, parchment, or other carbonaceous products, may be wholly or partially destroyed for reducing the absorptive quality to a total or partial extent; and further, to arrange the steps of the process, so that the shape and rigidity, lost by any degree of destruction of the fiber may be maintained by the non-porous and moisture repellent element simultaneously applied in its stead.

40 A further object is to provide a process by the use of which articles of paper, cardboard, or other carbonaceous fibrous material, manufactured into such shapes as milk bottles and the like, may be easily and effectively treated; and wherein the joints and lappings which may inevitably occur in such articles, will be so affected as to practically disappear and leave the structure a homogeneous mass, apparently without seams or other crevices 45 into which moisture may seep.

In carrying out this process, the material, such as paper, cardboard, or other fibrous or porous material as above described, is, first, without previous treatment submerged

in a suitable liquid; the temperature of the liquid is then raised to a degree to partially or wholly destroy the fibers of the submerged material. After the material is submerged, and before raising the temperature of the liquid, the surrounding air pressure may be reduced, if desired, so as to assist in removing the moisture from the interstices of the submerged material. The reduced air pressure may be continued until bubbles cease to rise from the material. The pressure of the surrounding air is then raised, if desired, somewhat above atmospheric pressure so as to assist in forcing the submerging liquid into the vacated interstices of the submerged material. The material is withdrawn from the liquid while the liquid is yet sufficiently hot to have only a negligible surface tension for the material. The material is then allowed to cool at atmospheric temperature and pressure.

Suitable time is, of course, allowed for each of the steps referred to, and the result is that the product, when cooled, shows little or none of the material into which it has been submerged, upon its surface.

In order to more clearly understand the apparatus necessary for carrying out this process, a drawing is attached hereto, Figure 1 of which diagrammatically illustrates the necessary vat, device for heating the contents thereof, and mechanism for lowering and raising the air pressure therein;

Fig. 2 illustrates a transverse, vertical, sectional view through a receptacle made of paper, the view being taken before subjection of the receptacle to the process herein described; and

Fig. 3 is an enlarged sectional view of a portion of the structure shown in Fig. 2, illustrating the condition of the same after subjection to the steps of this process.

Referring to the drawing, the reference character L indicates the vat within which a quantity of impregnating material may be contained. The reference character G indicates a suction pump for reducing the air pressure within the vat L. The reference character H indicates an air compressor for raising the pressure within the vat L. The vat L is provided with a suitable sealing cover or door 1 and may be fitted with a thermometer 2 and a pressure gage 3.

A heater, such as a Bunsen burner 4, may

be arranged beneath the vat L for heating the same, gas being fed to said burner through a suitable pipe 4^a controlled by the valve 4^b.

5 The suction pump G is connected to the upper portion of the vat L, above the level of the impregnating liquid contained within said vat, by a suitable pipe, and this pipe may be provided with tanks 5 and 6 intermediate its length as follows:

From the vat L a pipe 7 leads to the bottom of tank 6. A check valve 8 is provided in said pipe 7 to prevent return of any air into the vat, after being once withdrawn. 15 From the top of the tank 6 a pipe 9 leads through the top of tank 5 and downwardly within said tank 5 to a point near the lower end thereof. This pipe 9 is preferably provided with a relief valve 10 whereby the 20 suction from the pump G may draw air from the atmosphere rather than from the vat L when desired. From the top of tank 5 a pipe 11 leads directly to the suction pump G. Beyond the pump G a tank 12 is 25 arranged, said tank 12 being connected with the pump by pipe 13 and serving to contain a liquid through which the exhaust from the pump is expelled, a pipe 14 being connected to the upper end of the tank 12 to 30 serve as an exhaust conduit. A short length of pipe 15 is connected between the pipe 14 and the pipe 11, and this pipe 15 is provided with a governor valve 16, the purpose of 35 which is to maintain a uniform suction within the pipes 11, 9 and 7, and within the vat L according to the adjustment of the valve 16 as will be readily understood.

By these means air sucked up by the 40 pump G will travel along pipe 7, upwardly through the tank 6, through the pipe 9, through the liquid, preferably oil, as 5^a, in the lower portion of the tank 5, upwardly through the tank 5, through pipe 11, through the suction pump, and will be discharged 45 through the tank 12.

The tank 6 also serves as an expansion tank and also to collect any of the oil 5^a which may be forced out of the tank 5 due to back pressure, as when the vacuum is 50 relieved, and prevent such oil from flowing into the vat L in case the check valve 8 should fail.

The tank 5 also serves as an expansion tank, and the liquid as 5^a, serves to purify 55 the passing air and to condense and accumulate any of the liquid contents from the vat L which may enter said tank in a gaseous or vaporized state.

The liquid, as 12^a, within the tank 12 60 serves to further wash and purify the air before being discharged into the atmosphere. These tanks also serve as a means for maintaining a uniform vacuum pressure in the system, in that they represent an appreciable amount of space within which the

air may vary in pressure to a greater or less degree without materially affecting the pressure within the vat L.

The air compressor H is connected to the top of the vat L by a pipe 16, said pipe 70 being conveniently controlled by the valve 17. An expansion chamber, as 18, may be employed in connection with the compressor H, if desired.

A valve controlled pipe 19 may be connected between the pipe 16 and the burner 4, if desired, for coöperating with pipe 4^a, to feed a proper mixture of combustible material to the burner 4.

The liquid as 20 employed in connection 80 with this process within the vat L is preferably a waxy material, such as paraffin or some composition of paraffin or the like, heated until liquefied, but not materially further until after the material to be treated 85 is submerged therein. The liquid employed may be described simply as a liquefied solid, as this term carries the suggestion that when not heated the liquid will become a solid so as to lend rigidity to the treated material. 90

With the material to be treated submerged within the liquid, atmospheric air is of course effectively excluded from contact with any portion of the material. A small quantity of air will, of course, however, be retained within the interstices and pores of the submerged material. 95

When the temperature of the liquid is raised to the point of carbonizing the submerged material, the air and moisture locked 100 up in the interstices of the material immediately begins to withdraw and might be seen to rise to the surface in the form of innumerable bubbles from all parts of the submerged material. The higher the temperature of the submerging liquid, the more completely will the air and moisture be driven off, and the more completely will the submerged material become carbonized, and the greater will be the degree of penetration 110 by the submerging liquid.

Maximum penetration is desirable, but total carbonization for bringing about such a result is, of course, undesirable. It is preferable, therefore, to reduce the air pressure within the vat during the time when the submerging liquid is being heated and while it is at its greatest heat, so as to assist in withdrawing the air and moisture from the pores of the submerged material, and thereby accomplish by a given degree of heat what would otherwise be accomplished only by a relatively greater degree of heat and consequent objectionable carbonizing. 115

In carrying out this process it is consequently intended that the degree of heat applied shall be only such as will produce carbonization to an unobjectionable extent.

After the material has been subject to the desired heat and reduced pressure as above 130

described, until bubbles cease to rise, the pressure within the vat is then raised, by closing valve 10 and opening valve 17. The increased pressure will serve to force, or 5 push, the still very thin liquid into the more minute and inaccessible interstices.

The treating material is withdrawn from the vat while the liquid is yet at its maximum temperature, that is, when it has minimum 10 surface tension upon the treated material. In this way when the finished material is cooled to ordinary atmospheric temperature it is not noticeably coated with a deposit of the submerging liquid, now a solid. 15 The treated material may be employed in the manufacture of various articles which are to be used in the presence of moisture. In fact, the articles may have been already fashioned before being subjected to this 20 process as has been hereinbefore suggested. In either event, the finished article may be used with perfect satisfaction for any length of time even in immersed condition, without losing its shape, and without absorbing any 25 of the liquid within which it is immersed. In use, even the temperature of the immersing liquid, if such there be, or of the surrounding atmosphere when the article is not immersed, may be raised and lowered within 30 wide limits without affecting the article to an objectionable extent.

When the material, during treatment, is subjected to the maximum temperature of the liquid within the vat L, and a certain 35 proportion of the fiber thereof becomes carbonized or destroyed, this portion of the fiber is immediately replaced by the submerging liquid, which liquid, when the article is withdrawn, becomes a solid, and being 40 integral with all other like solids with which the material is now impregnated, transforms the material, particularly the stratas, or layers thereof which may have existed before subjection to treatment, into a single 45 homogeneous mass.

In the treatment of articles already fashioned from paper and the like, such for instance, as the container illustrated in Fig. 2 of the drawings, any joints as 21 of lappings 50 as 22 of the paper or the like, incident to the formation of the articles, practically lose their identity in the greater or less destruction of the fiber of the material. The result is that the lapping or joint portions are in 55 effect welded together into a homogeneous mass, as indicated in Fig. 3 of the drawings, the seams and joints being practically incapable of separation.

The process is simple and inexpensive, 60 and results not in a simple coated article, but in a practically new article of manufacture. The original fibrous and absorbent structure is transformed into a practically non-fibrous and non-absorbent article.

65 It is intended that all matter contained in

the above description, and shown in the accompanying drawing, shall be interpreted as illustrative only, and not in a limiting sense, and that the following claims are intended to cover all the generic and specific features 70 of the invention which may be said to fall within the language of said claims.

Having thus described my invention, what I claim as new and desire to secure by Letters Patent, is:—

75

1. The process of treating fibrous substances which consists of, first, submerging the substance in a liquid, raising the temperature of the liquid to a degree to partly destroy the fibers of the substance while the 80 substance is submerged, and causing the submerging liquid to form a substitute for the destroyed fibers.

2. The process of treating fibrous substances which consists of, first, submerging the substance in a liquid, withdrawing at least a portion of the air, beyond normal penetration of the liquid, from the interstices of the fibrous material, raising the temperature of the submerging liquid to 90 partly destroy the fibers of the substance, and applying pressure to the submerging liquid for forcing the liquid into the interstices vacated of air.

3. The process of treating fibrous substances for rendering said substances moisture proof which consists of, first, submerging the substance in a liquefied moisture repellent solid, withdrawing at least a portion of the air, beyond normal penetration of the 100 liquid, from the interstices of the fibrous substance, raising the temperature of the submerging liquid to increase its fluidity and to partly destroy the fibers of the substance, forcing a portion of the fluid under pressure 105 into the interstices of the substance, withdrawing the substance from the liquid while the liquid is yet heated, and allowing the substance to cool to solidify the liquid to form a substitute for the destroyed portion 110 of the fibers of the substance.

4. The herein described process of treating carbonaceous fibrous substances, which consists in first submerging the substance in a liquid, withdrawing at least a portion of the 115 air beyond normal penetration of the liquid, from the interstices of the material, raising the temperature of the submerging liquid to the point of carbonizing the fibers of the substance, and subsequently separating said 120 substance from the submerging liquid.

5. The herein described process of treating carbonaceous fibrous substances which consists in first submerging the substance in a liquid, withdrawing at least a portion of the 125 air beyond normal penetration of the liquid, from the interstices of the material, raising the temperature of the submerging liquid to the point of carbonizing the fibers of the substance, and subsequently separating said 130

substance from the submerging liquid, while said liquid is yet substantially at its maximum heat.

6. The herein described process of treating 5 carbonaceous substances, which consists in charring said substance, and simultaneously applying an impregnating material to said substance.

7. The herein described process of treating 10 carbonaceous fibrous substances, which consists in charring said substance, and forcing an impregnating material between the fibers of said substance.

8. The herein described process of treating carbonaceous substances, which consists in 15 charring said substance, simultaneously applying an impregnating liquefied solid to said substance, and then allowing said liquefied solid to solidify.

In testimony whereof I affix my signature 20 in the presence of two witnesses.

GEORGE E. FERGUSON.
